DESIGN FOR A TOY GUN

Wallace C. Hooper, Los Angeles, Calif.

Application August 20, 1945, Serial No. 121,509

Term of patent 3½ years

(Cl. D34—15)

To all whom it may concern:

Be it known that I, Wallace C. Hooper, a citizen of the United States, residing at Los Angeles, in the county of Los Angeles and State of California, have invented a new, original, and ornamental Design for a Toy Gun, of which the following is a specification, reference being had to the accompanying drawing, forming part thereof.

Figure 2 is a top plan view of the toy gun, Figure 3 is an elevation of the toy gun looking in the direction of the stock, and Figure 4 is an elevation of the toy gun looking in the direction of the muzzle.

I claim:

The ornamental design for a toy gun, as shown and described.

WALLACE C. HOOPER.
